UNITED STATES PATENT OFFICE.

EDMOND M. DELORAIN, OF BLACKHEATH, LONDON, ENGLAND, ASSIGNOR TO WESTERN ELECTRIC COMPANY, INCORPORATED, OF NEW YORK, N. Y., A CORPORATION OF NEW YORK.

ELECTRON-DISCHARGE DEVICE.

Application filed May 19, 1925. Serial No. 31,267, and in Great Britain November 3, 1924.

This invention relates to electron discharge devices and more particularly to such devices capable of operating at high voltages.

In such devices, one electrode is heated to produce a stream of electrons which are impelled at high velocity toward the other electrode by virtue of a difference of potential between them. It is well known that the effect of the electronic bombardment on an electrode is to increase the temperature of the latter, the kinetic energy of the electron flow being converted into heat. The temperature of a bombarded electrode rises until the rate at which energy is transferred to it by the bombarding electrons becomes equal to the rate at which it is dissipated from it.

In electron discharge devices at present in use, no advantage is taken of the heating up of the anode. On the contrary, means are often provided for dissipating this heat and keeping the temperature of the anode comparatively low. The heat thus withdrawn from the anode represents a loss of energy and is merely carried away by radiating or cooling means.

The present invention aims to utilize the energy ordinarily dissipated on the anode by employing it to produce a thermionic emission to be used efficiently in the further operation of the device. It is known that in the case of the medium sized electron discharge devices of the ordinary type, the power dissipated on the anode is of the same magnitude as the power used to heat the cathode and may be much greater in the case of the larger power tubes at present in operation.

It is clear that if instead of the anode heat being wasted it were employed for resupplying the cathode with heat energy, a large economy of filament current would be the result and for the continued functioning of the device an external source of energy might even be eliminated.

According to one embodiment of the invention, this object is achieved by constructing the electron discharge device in such a way that when used in connection with a suitable circuit, the electrodes reverse their functions of anode and cathode, respectively, at short intervals. This is accomplished by supplying alternating current to the respective electrodes so that during one half cycle of the current, one electrode is charged with a high positive potential with respect to the other electrode, and an electron stream is caused to

flow from the electrode at low potential to the electrode at higher potential. Upon the reversal of current from the alternating source, the polarity of the electrode is reversed. This arrangement utilizes the heat energy dissipated on the anode when the electrons are flowing in one direction to cause an electron flow in the opposite direction upon reversals of current.

Referring to the drawings, the single figure illustrates one embodiment of the invention as applied to an oscillation generator.

A glass vessel 10 contains two electron emitting electrodes 11 and 12, preferably in filamentary form. These electrodes may be formed into any desirable shape, whereby a sufficiently large surface area is obtained. A plurality of control electrodes or grids 13 and 14 are located between the electrodes 11 and 12. These electrodes may be supported within the vessel 10 in any desirable manner and suitable leads are brought through the vessel for connection to any desired circuit. To connect the device in an oscillation circuit, the electrodes 11 and 12 are connected together through a tuned circuit comprising two arms 15 and 16 of an inductance and a condenser 17. Preferably only one connection is made to each electrode, while the remaining ends are short circuited for reasons to be hereinafter described. The control electrode 13 is connected in the oscillation circuit through a feed back winding 18 of the inductance. A suitable resistance connected in the grid circuit keeps the power dissipated on the grid sufficiently low and serves to impress on the control electrode a negative potential with respect to the electrode 11. A condenser 20 is connected across the resistance 19 to provide a conductive path for discharges to the grid 13. A similar circuit connects the control electrode 14 with the tuned circuit by means of feed back coupling 21, resistance 22 and condenser 23. A power transformer 24, having the high side thereof connected to the inner ends of the inductances 15 and 16 and the low side connected to any suitable alternating current source supplies high voltage current to the electrodes 11 and 12. A by-pass condenser 25 of suitable capacity is connected across the high winding of transformer 24 and in series with the inductances 15 and 16. This condenser is designed to offer low impedance to the high frequency currents and a high impedance to low frequency currents.

When starting, the electrodes 11 and 12 may be heated to incandescence by any suitable means, the object being to heat the electrodes so that electronic emission can take place. For example, this may be carried out by heating the electrodes 11 and 12 with a high frequency coil 26 surrounding the vessel 10. Current supplied to this coil will induce current in the electrodes 11 and 12, 10 acting as secondaries of the high frequency transformer 26, whereby they will be heated to a temperature high enough to emit electrons. The high frequency coil is only necessary to initially heat the electrodes to incandescence, since the alternating current applied to the electrodes through transformer 24 and inductances 15 and 16 continually keeps the electrodes in an active state so that on each half cycle of the alternating current, 20 when one of the electrodes is positively charged with respect to the other electrode, the second electrode is an electron emitter. Upon a reversal of the current, the electrodes change their function so that the electrode 25 performing as a cathode now becomes an anode and the former anode is now a cathode or electron emitter.

Referring to the operation of the device as an oscillator, it will be seen that when the electrode 11 is heated, the grid performing its function in the well-known manner and a high positive potential applied to the electrode 12, the system will oscillate as the controlling action of the grid 13 is stronger than the action of the grid 14. The electrode 12 (which is now the anode) is at a high temperature, which will be further increased by the bombardment of electrons from the electrode 11 (which is the cathode). When the circuit is reversed due to the alternating potential from the power source, the electrode 12 which is at a high temperature, will emit electrons and oscillations will occur in a way absolutely similar to that described previously, since the electrode 11 (which is now the anode) will be charged with a high posi-

tive potential. It will be seen that one active electrode will be the cathode with respect to the other electrode, and upon reversal of current, their function will be changed with respect to each other.

Although the invention has been described as applied to an oscillation generator, it is to be understood that the invention is applicable to other uses, such as high frequency amplifiers, repeaters and the like, and is only to be limited within the scope of the appended claims.

What is claimed is:

1. In combination, an electron discharge device comprising two electrodes, means for heating said electrodes to incandescence, means for alternately impressing a high positive potential on each of said electrodes whereby an electron flow passes between said electrodes, and a pair of grids between said electrodes, each of said grids alternately controlling said electron flow. 60

2. In combination, an electron discharge device comprising two electron emitting electrodes, means for heating said electrodes to incandescence, alternating current applied to each of said electrodes whereby an electron flow passes between said electrodes, and a pair of grids between said electrodes, each of said grids alternately controlling said electron flow when the nearest electrode is functioning as the cathode. 70

3. In combination, an electron discharge device having two electron emitting electrodes and two grids, means for initially heating said electrodes, an output impedance for the amplified waves connected between said electrodes, a pair of input circuits connected between said grids and said electrodes respectively, means for periodically reversing the potential of said electrodes to correspondingly reverse the function of said electrodes as cathode and anode. 80

In witness whereof, I hereunto subscribe my name this 18th day of May, A. D. 1925.

EDMOND M. DELORAINNE.
